DISPENSING CONTAINER

Vincent Pantalone, New Haven, Conn., assignor to
 National Folding Box Company, New Haven,
 Conn., a corporation of New Jersey

Application May 18, 1932, Serial No. 611,962

11 Claims. (Cl. 206—58)

This invention relates to dispensing containers and more particularly to a container adapted to receive a roll of material and dispense the same as required.

5 Containers heretofore provided for the dispensing of rolled sheet material, such as ribbon, gauze, adhesive strips, bandaging material and the like have been very expensive to make and oftentimes the cost of the container exceeds the 10 cost of the material packed therein. The dispensing mechanisms of prior containers also operate indifferently, oftentimes getting out of order and necessitating taking the container apart in order to extract the contents. Again, certain 15 types of rolled sheet material, such as used for the bandaging of wounds, should be fully protected against dust, dirt, germs and contaminating influences, and containers heretofore made have been lacking in these protective features.

20 This is especially true of those containers which have no adequate provision for protecting the free end of the rolled strip. Where the end of the strip is left exposed to contaminating influences, the protective features which the container might otherwise have, are of little or no 25 value.

An object of my invention is to provide a dispensing container for strip material which can be inexpensively made, which provides full protection to the contents at all times, and which can be easily and quickly assembled together and packed.

Another object of my invention is to provide a dispensing container for rolled strip material which is sanitary and fully protects the contents from contamination, which is convenient to use, and which may be made into a number of attractive designs and patterns.

Still another object of my invention is to provide a dispensing container for rolled strip material from which the contents may be withdrawn as needed, and which is provided with a protective means which fully encloses the free end of the strip when not in use.

45 Another object of my invention is to provide a substantially foolproof dispensing container from which rolled strip material may be easily and conveniently withdrawn, and which is furthermore provided with means for rewinding the strip 50 on to the roll if more material has been dispensed than required.

Still another object of my invention is to provide a cutout blank from which a convenient and attractive dispensing container for strip material 55 may be made.

Other objects of this invention will become apparent as the disclosure proceeds.

Although the novel features which are believed to be characteristic of this invention will be particularly pointed out in the claims appended here-to, the invention itself, as to its objects and advantages, and the manner in which it may be carried out, may be better understood by referring to the following description taken in connection with the accompanying drawing forming 10 a part thereof, in which.

Fig. 1 is a face view of one form of blank from which the dispensing container may be made;

Fig. 2 is a face view of a disc which is positioned within the container and which may be 15 manipulated to revolve the rolled material within the container;

Fig. 3 is a perspective view of my dispensing container as it appears when fully assembled;

Fig. 4 is a perspective view of the blank shown 20 in Fig. 1 in the process of assembly to form the container;

Fig. 5 is a perspective view of the container with the cover portion thereof raised and showing the strip material therein about to be dispensed;

Fig. 6 is a vertical longitudinal cross sectional view through the dispensing container, this view being taken on line 6—6 of Fig. 7; and

Fig. 7 is a vertical transverse cross sectional 30 view of the container, this view being taken on line 7—7 of Fig. 6.

Similar reference characters refer to similar parts through the specification and drawing.

I have shown in Fig. 1 a blank which may be 35 made of paperboard or other sheet material suitably cut and scored to form the complete dispensing container, including the body portion and the cover portion thereof. The body portion of the blank generally comprises a rear wall 10, side 40 walls 11 and 12, front wall 13 and a securing tab 14, all separated and defined by the score lines 15. The bottom of the container is formed from the front and rear wall flaps 16, defined from the front wall 10 and the rear wall 13 by the score 45 lines 18, and the side flaps 17, defined from the side walls 11 and 12 by the score lines 18. The body portion is provided with a pair of closure flaps 19 and 20, defined from the side walls 11 and 12 respectively by the score lines 21. Interlocking tongues 26 and 27 are provided on the inner closure flaps 19 and 20 respectively. The outer closure portion of the blank comprises a top wall 22 hinged to the rear wall 10 along the score line 21, and a front flap 23 hinged to the 55

top wall 22 along the score line 24. An insert tab 25 extending from the front flap 23 is adapted to be inserted into a slot 28 provided in the front wall 13 to hold the top closure portion in closed 5 position.

The container is assembled by folding the blank, shown in Fig. 1, into a tubular form along the score line 15, and then cementing or otherwise fixing the securing tab 14 to the free edge 10 of the side wall 11. The front and rear wall flaps 16 and the side wall flaps 17 are then folded inwardly in superimposed relationship and cemented together to form the bottom wall of the container.

15 The roll strip M, indicating the material to be dispensed, is then inserted into the container. It is understood that the blank is of sufficient size to provide a container of such width, length and height as to comfortably receive and house the 20 rolled strip therein. The side walls 11 and 12 of the blank are preferably provided with an aperture 29 therein which may be cut out during the formation of the blank. A pair of discs 30, which may be made of relatively stiff paperboard, 25 are inserted into the container, a disc being inserted at each end of the rolled strip M. When discs 30 have been so positioned they will cover the apertures 29 provided in side walls 11 and 12, as clearly shown in Figs. 3, 5 and 7. After the 30 strip M has been inserted into the container, as shown more clearly in Fig. 6, the free end of the strip is pulled out so as to be positioned adjacent the rear wall 10 and to extend outside of the body portion. The side closure flaps 19 and 20 35 are then folded inwardly and the tongues 26 and 27 thereof interlock, as shown in Fig. 5, to provide an inner closure which fully protects the roll from dust, dirt and contaminating influences at all times.

40 When the strip is to be dispensed, the end portion of the strip is pulled forward, which causes the roll to revolve and unwind. When sufficient material has thus been withdrawn, the required length is clipped off and used as desired. The 45 remaining end portion which has already been unwound from the roll can then be folded on top of the inner closure flaps 19 and 20. To protect this free end of the strip, the outer closure portion 22 is folded down over the end of the strip 50 so as to house the same between the top wall 22 and the inner closure flaps 19 and 20. The front flap 23 further overlaps the front wall 13 and prevents foreign matter from getting into the container. The outer closure portion may be 55 held in closed position by means of the tab 25 which is inserted into the slot 28 provided in the front wall 13.

If more than the required amount of strip material has been unwound from the roll, the 60 roll can be rewound by inserting instruments such as the thumb and fore-finger through the apertures 29 in the side walls 11 and 12, and exerting an inward pressure on the discs 30. If the thumb and forefinger or other instrument used is then 65 given a twisting or revolving motion, the discs 30 will grip the ends of the rolled strip and also revolve the roll during this manipulation. The unrolled portion of the strip can thus be rewound or rolled back on to the roll within the container. 70 This is an important feature of this invention which has not been provided in containers heretofore used. The rear edge 31 of the inner closure flaps 19 and 20 serves as a guide during the unwinding and rewinding of the strip material, and 75

promotes smoothness, ease and facility of operation.

It is now seen that I have provided a dispensing container comprising a body portion provided with inner closure flaps and a cover portion, formed complete from a single blank of sheet material. The blank can be formed in a single operation on a cutting and scoring machine. The blank can also be assembled on a gluing machine without necessitating any hand labor whatever. 10 The discs 30 are preferably made of paperboard material which has a slightly roughened surface which grips the ends of the roll when lateral pressure is exerted thereon. The container can be quickly and economically made on a large 15 production basis. The rolled material can be quickly and easily inserted therein and the closure flaps 19 and 20 locked together to serve a double purpose, namely, to protect the rolled contents within the container and also to serve 20 as a guiding means in the unwinding and rewinding of the rolled strip. The outer cover portion 22 fully protects the free end of the strip from germs, dust, dirt and contamination since the end of the strip is housed between the inner 25 closure flaps 19 and 20 and the outer closure portion 22. The outer closure can be fixed in closed position by the simple operation of inserting the tab 25 into the slit 28 provided in the front wall of the container. 30

The means provided for manipulating and revolving the roll which includes the paper discs 30 and the apertures 29 are substantially foolproof in operation and can be provided at very little cost. The container fully protects the 35 contents at all times and provides an attractive package for the dispensing of rolled materials, which can be inexpensively made into any number of attractive designs and patterns.

It is understood that the dispensing container 40 herein disclosed may be used for the dispensing of a large variety of different rolled materials, such as cloth, ribbon, strips, gauze, bandages, tape and other rolled articles.

While certain novel features of the invention 45 have been disclosed and are pointed out in the annexed claims, it will be understood that various omissions, substitutions and changes may be made by those skilled in the art without departing from the spirit of the invention. 50

What is claimed is:

1. A dispensing container for roll material including in combination, a body portion including paperboard side walls and a paperboard bottom wall, and substantially flat disc pieces seated 55 against the ends of said roll strip and accessible from the exterior of the body portion for manipulating and revolving said roll.

2. A dispensing container for roll material including in combination, a body portion, including side walls and a bottom wall and exteriorly accessible means for manipulating and revolving the roll therein, said means including disc pieces positioned within said body portion and against the ends of said roll, and apertures provided in 65 said walls permitting access to said discs from the exterior of the body portion.

3. A dispensing container for a rolled strip including in combination, a body portion formed from a single blank of paper board material, 70 said body portion comprising side walls and a bottom wall, and substantially flat disc pieces seated against the ends of said rolled strip and within said body portion for manipulating and revolving said roll. 75

4. A dispensing container for a rolled strip including in combination, a body portion formed from a single blank of paperboard material, said body portion comprising side walls and a bottom wall, disc pieces positioned within said body portion and seated against the ends of said roll, and apertures provided in said walls permitting access to said discs from the exterior of the body portion, said disc pieces providing means for manipulating and revolving said roll therein.

5. A dispensing container for a rolled strip including in combination, a body portion formed from a single blank of paper board material, said body portion comprising side walls and a bottom wall, disc pieces within said body portion accessible from the exterior of the body portion for manipulating and revolving said roll, said disc pieces gripping a substantial end area of said rolled strip, and means for guiding the unrolled portion of said strip into dispensing position.

10 6. A dispensing container for a rolled strip including in combination, a body portion formed from a single blank of paperboard material, said body portion comprising side walls and a bottom wall, disc pieces within said body portion accessible from the exterior of the body portion for manipulating and revolving said roll, said disc pieces frictionally contacting a substantial end area of said rolled strip, and a closure portion adapted to cover and house the unrolled portion of said strip.

15 7. A dispensing container for a rolled strip including in combination, a body portion comprising side walls and a bottom wall, means accessible from the exterior of said body portion for manipulating said roll therein, said means frictionally gripping a substantial end area of said rolled strip, flaps for enclosing said roll within the body portion, and a closure portion housing the unrolled portion of said strip deposited on said flaps.

20 8. A dispensing container for a rolled strip including in combination, a body portion comprising

25 side walls and a bottom wall, means comprising disc pieces accessible from the exterior of said body portion for manipulating said roll therein, said disc pieces frictionally gripping a substantial end area of said rolled strip, interlocking flaps forming an inner closure for said roll portion, and an outer closure portion housing the unrolled portion of said strip deposited on said flaps.

5

30 9. A dispensing container for a rolled strip including in combination, a body portion comprising side walls and a bottom wall, disc pieces seated against the ends of said rolled strip and accessible from the exterior of said body portion for manipulating said roll therein, interlocking flaps forming an inner closure for said roll portion, an outer closure portion housing the unrolled portion of said strip deposited on said flaps, and means for guiding the unrolled portion of said strip into dispensing position.

20

35 10. A dispensing container for a rolled strip including in combination, a body portion comprising side walls and a bottom wall, means including disc pieces seated against said rolled strip and accessible from the exterior of said body portion for manipulating said roll therein, interlocking flaps forming an inner closure for said roll, the edge of said flaps providing a means for guiding the unrolled portion of said strip into dispensing position.

25

40 11. A dispensing container for a rolled strip including in combination, a body portion comprising side walls and a bottom wall, means including disc pieces seated against the ends of said rolled strip and accessible from the exterior of said body portion for manipulating said roll therein, interlocking flaps forming an inner closure for said roll portion, an outer closure portion housing the unrolled portion of said strip deposited on said flaps, and means for securing said outer closure in closed position.
